ARRANGEMENT FOR SORTING PAPER PULP
AND SIMILAR SUSPENDED MATTERSVäinö Vilho Rantaniemi, Tammerfors, Finland,
assignor to Tammerfors Linne-Och Jernmanu-
faktur Aktiebolag, Tammerfors, Finland, a cor-
poration of FinlandApplication February 2, 1945, Serial No. 575,806
In Finland March 18, 1944

3 Claims. (Cl. 92—29)

1

The present invention relates to an arrangement for sorting paper-pulp and similar suspensions wherein the suspended matter passes through a vertically disposed sifting cylinder, or screen and from the opposite side of which, usually the outer side, the suspended matter, which has been freed from coarse particles, is removed. In prior known sorters the suspended matter remains for the most part on both sides of the sifting cylinder, as a rule slightly higher on the intake side than on the outlet side, and the pressure on the latter side therefore remains, while the sorter is in motion, constantly in a certain decided relation to the pressure on the intake side.

The present invention constitutes an improvement in sorters of the above mentioned type and embodies means for varying the state of the suspended matter on the outlet side of the sifting cylinder and thereby the existing pressure during motion whereby the capacity of the sorter may be increased or diminished and the degree of fineness in the sorted pulp may be varied and wherein both of these capabilities may be predetermined and controlled.

The invention is illustrated in the accompanying drawings in which Figure 1 is a side view thereof partly in vertical section and partly in elevation, and Figure 2 is a view on lines II—II of Figure 1.

In the drawings:

1 is the sifting cylinder or screen which is supported by the springs 2 and suspended from the upper lid 3. The bottom end of the cylinder is rendered elastic and solution-tight, by means of the rubber band 4 carried by the lower end of the cylinder and attached to the bottom of the sorter 5. The vibrator 6, by which the sifting cylinder can, in the prescribed manner, be brought into a vibratory motion and by which its effect can be considerably increased, is fastened to the top member 7 of the sifting cylinder 1.

The suspended matter to be sorted enters through the intake 8 passes into the central chamber 9 (Fig. 1) thence through the openings 10 to the inside of the sifting cylinder, that is, the primary chamber 11 where it is brought into a rotary motion, sweeping along the straining surface of the sifting cylinder or screen as a consequence of the construction of the intake openings 10 which have guiding surfaces or vanes 19 directed obliquely towards the cylinder 1. The effect of the rotary motion can be enhanced by means of the jet-pipes 17 which can add diluting water to the suspended matter in chamber 11, the water passing through the channels 16 which are 55

2

connected to the water intake 15 and the jet pipes or spray nozzles are curved for the most part in the direction of the guiding surface 19. The finer particles of the suspension in chamber 11 penetrate through the screen and enter the encircling chamber 12 while the coarser particles float upwardly in chamber 11 and pass out through the central outlet 14, the discharge therethrough being advantageously promoted by means of a jet of water directed obliquely towards the surface of the suspension and introduced through the jet-pipe 18, the outlets of which are directed towards the outlet 14.

In prior known sorters or strainers the finely strained suspension discharge is from the chamber 12 at only one point, that is, through an outlet 13. The container in the present invention has been partitioned by means of a cylindrical wall 20 to provide an outer discharge chamber 122 and a secondary chamber 12. In the partition wall 20 there are a number of series of outlet valves disposed at different heights, and as illustrated at three different heights, with four valves 21 in each series. The valves are arranged so that they can be regulated in series, each series by independent operating means including a control wheel 22 placed at the side of the sorter and driving a gear wheel 23, meshing with teeth 24 on the upper surface of a ring 25 to which the valve plates 21 are connected. Each ring 25 is slidably supported by circumferentially spaced supporting members 26. By decreasing or increasing the size of the openings regulated by valves 21 in the partition wall 20, and through which openings the strained matter flows from the inner chamber 12 to the outer chamber 122, the consistency of the strained matter, the counter pressure in the first named chamber and thereby the effect of the strainer as well as the degree of fineness of the strained suspension can be varied within a very wide range.

The outlets through which the strained matter is withdrawn at different heights from chamber 12 could also be made as separate annular outlet channels, and valves 21 could be adapted to be made regulative according to height whereby the partition wall 20 could also be constructed of annular parts with intervening slits, serving as outlets, the open height of which is regulated by the help of similar members corresponding to valves 21 which can be raised or lowered independently.

In such cases where a dilution of the finely strained suspension in chamber 12 is not disadvantageous the consistency of the pulp in this chamber can be influenced by the introduction

of regulated quantities of diluting water to the suspension, therefore the outlet 13 should be made regulatable and dimensioned so that it is capable of withdrawing the increased amount of liquid. This regulation is obtained through the weir 27 although any other suitable flow controlling means could be employed. If desired the passage of the pulp in the strainer can also be reversed in which case the interior chamber of the strainer 1 must be partitioned as described in connection with the chamber 12, and the outer chamber provided with overflows, instead of outlet 13, for the removal of the coarse particles. If it is not desired to remove the suspension passing out through the different outlets by means of a common outlet, the suspension can also be divided up so that each separate stream passing out from these outlet openings is led away separately or mixed in a suitable manner. By means of a similar division one can also obtain, for example, 3-4 different kinds of suspensions. Thus this strainer can be utilized for fractionating.

I claim:

1. A strainer for paper pulp including a main container, means within the container for receiving the material to be strained in suspension and for straining the pulp, means for separately discharging heavy particles from the straining means, a partition wall spacedly and concentrically surrounding said straining means and defining a secondary container and an outlet chamber, said wall having a plurality of series of circumferentially spaced discharge outlets, said series being vertically spaced from each other for selectively discharging strained material simultaneously at different heights into the outlet chamber, independent means for selectively adjusting the size of the outlets in the different series, the outlet chamber having a discharge outlet below the level of the lowermost series of outlets in the said wall and adjustable flow control means for said outlet for discharging the suspension of strained materials from

the strainer at a rate corresponding to that of the suspension entering at different levels into the outlet chamber.

5 2. A strainer as defined in and by claim 1 wherein a vertically disposed cylindrical straining screen is provided in the strainer and constitutes the straining means and wherein means are connected to the screen for vibrating the same.

10 3. A pulp strainer as defined in and by claim 1 wherein a vertically spaced series of circumferentially spaced supporting means are secured to the partition wall on the outlet side of the outlets therein, and wherein a ring element carrying a plurality of plate members each coacting with an outlet in the wall in a series of outlets and being carried by each series of the supporting means and constituting a control means for the size of the outlets in each series 15 of outlets, and wherein independently operated means are connected to each ring to selectively rotate the same in either direction to thereby control the size of the outlets in each series of outlets and to selectively discharge strained suspension at different heights from the secondary container into the outlet chamber.

20 25 VÄINÖ VILHO RANTANIEMI.
